AZODYESTUFFS INSOLUBLE IN WATER

Werner Zerweck, Frankfort-on-the-Main-Fechenheim, and Norbert Steiger, Frankfort-on-the-Main, Germany, assignors to General Aniline Works, Inc., New York, N. Y., a corporation of Delaware

No Drawing. Application May 15, 1934, Serial No. 725,821. In Germany May 23, 1933

8 Claims. (Cl. 260—95)

The present invention relates to new azodye-stuffs insoluble in water more particularly to such corresponding to the general formula:

hot, rinsed again and dried. In this manner a clear golden-orange dyeing of excellent fastness qualities is obtained.

10 (wherein one of the X's means hydrogen or alkyl or phenyl, the other X alkyl or phenyl and the benzene nucleus attached to the CONH-group may contain as substituents halogen, alkyl or 15 alkoxy groups).

The new products may be obtained by diazotizing an arylamine containing two sulfone groups of the aforesaid kind and combining the diazo-compound, in substance or on a substratum especially on the fiber, with an arylamide of 20 2-hydroxy-3-naphthoic acid.

They are distinguished by clear fast yellow to golden-orange shades being as yellowish as hitherto not obtainable by means of dyestuffs of 25 this series.

In order to further illustrate our invention the following examples and table are given; but we wish it however to be understood that our invention is not limited to the particular products 30 nor reacting conditions mentioned therein.

Example 1

40 grams of boiled cotton yarn are impregnated in the usual manner in the following impregnating bath (a) and then developed in the following dyeing bath (b):—

(a) *Impregnating bath*

2 grams of 1-(2'-hydroxy-3'-naphthoylamino)-2-methyl-4-chloro-benzene,
40 4 cc. of Turkey red oil of 50%,
6 cc. of caustic soda lye of 34° Bé.,
2 cc. of a solution of formaldehyde of 30%,
500 cc. of boiling water, made up with water to 1 liter.

(b) *Dyeing bath*

3.3 grams of 1-amino-2-benzylsulfone-4-methylsulfone-benzene are dissolved at room temperature in 10 cc. of concentrated sulfuric acid 50 and at 0° C. 1 gram of sodium nitrite is added to the solution. After shortly standing at 5–10° C. the diazo-solution is diluted with ice-water to about 800 cc. and the sulfuric acid is neutralized by means of 40 grams of sodium acetate.

55 Then the dye goods are rinsed, soaped in the

Example 2

In the same manner as described in the foregoing example 40 grams of cotton yarn are impregnated in an impregnating bath, containing 15 2 grams of 1-(2',3'-hydroxy-naphthoylamino)-4-chloro-benzene, and then developed in the following dyeing bath:

Dyeing bath

20 4 grams of 1-amino-2,4-di-(propylsulfone)-benzene are dissolved at about 40–50° C. in 40 cc. of concentrated sulfuric acid. The solution is cooled down to 5° C. and 1 gram of sodium nitrite is added. After about 3/4 hour's stirring the solution 25 is diluted with ice-water and the difficultly soluble diazo-compound is sucked off. Then it is carefully stirred with about 1200 cc. of water. A clear golden-orange dyeing is obtained.

The following table shows the shades of some 30 further dyestuffs obtained according to the present process:

Diazocomponent	2'-hydroxy-3'-naphthoyl-compound of—	Shade	35
	Aminobenzene..... 4 - chloro - 2 - methyl - 1 - aminobenzene.....	Yellowish orange Orange	40
	4 - chloro - 2 - methyl - 1 - aminobenzene..... Aminobenzene.....	Yellowish orange Orange	45
	4 - chloro - 2 - methyl - 1 - aminobenzene..... 2 - methyl - 1 - aminobenzene..... 3,4 - dichloro - 1 - aminobenzene.....	Orange Yellowish orange Orange	50
			55

Diazocomponent	2'-hydroxy-3'-naphthoyl-compound of—	Shade
5 NH ₂ 	Aminobenzene-----	Yellowish orange
10 NH ₂ 	4-chloro-1-aminobenzene----- 4-chloro-2-methyl-1-aminobenzene-----	Yellowish orange Do.
15 NH ₂ 	4-chloro-1-aminobenzene-----	Orange
20 NH ₂ 		

which dyestuff dyes when prepared on the fiber clear golden orange shades.

3. The azodyestuff of the formula:

which dyestuff dyes when prepared on the fiber clear yellowish orange shades.

4. The azodyestuff of the formula:

30 In the same manner similar clear shades may be obtained according to one of the usual printing methods.

The dyestuffs yield when produced per se and when mixed with the usual substrata clear lakes of similar shades and good fastness qualities.

We claim:—

1. The azodyestuffs insoluble in water corresponding to the general formula:

wherein one of the X's is selected from the group consisting of hydrogen, alkyl and phenyl, the other X is selected from the group consisting of alkyl and phenyl, and R means a radical of the benzene series, which dyestuffs are distinguished by clear fast yellow to golden-orange shades being as yellowish as hitherto not obtainable by means of dyestuffs of this series.

2. The azodyestuff of the formula:

which dyestuff dyes when prepared on the fiber clear orange shades.

5. Fibers dyed with the dyestuffs claimed in 40 claim 1.

6. Fibers dyed with the dyestuff claimed in claim 2.

7. Fibers dyed with the dyestuff claimed in claim 3.

8. Fibers dyed with the dyestuff claimed in claim 4.
